United States Patent

Des. 236,767
Patented Sept. 16, 1975

236,767

CRADLE

John W. McKelvey, 4306 Lynd Ave.,
Arcadia, Calif. 91006

Filed Feb. 14, 1974, Ser. No. 442,523

Term of patent 14 years

Int. Cl. D6—01

U.S. CL. D6—15

FIG. 1 is a right side elevational view of a cradle showing my new design;

FIG. 2 is a top plan view;

FIG. 3 is a bottom plan view;

FIG. 4 is a front elevational view; and

FIG. 5 is a rear elevational view.

I claim:

The ornamental design for a cradle, as shown.
